MASS SPECTROMETRY

Edmund E. Hoskins, Pasadena, Calif., assignor to
 Consolidated Engineering Corporation, Pasadena, Calif., a corporation of California

Application July 3, 1943, Serial No. 493,415

6 Claims. (Cl. 73—18)

This invention is concerned with mass spectrometers and provides improvements to the end that sensitive elements in the mass spectrometer, particularly the ion emission apparatus, the ionization chamber, the analyzer and the equipment for evacuating these elements, are protected from damage due to power failures, gas leaks, and other accidents.

A mass spectrometer is an apparatus for sorting ions, and may be employed for quantitative and qualitative analyses of mixtures, for the determination of isotope ratios and for various other purposes. It usually comprises an ionization chamber and an analysis chamber plus an ion collector. In the ionization chamber molecules of a substance being investigated are bombarded by ionizing particles such as electrons. These usually are emitted from an electrically heated filament, and shot as a beam against the molecules. The resulting ions are propelled by a potential impressed across a plurality of electrodes into and through an analyzer chamber, where they are sorted by an electrical or magnetic field or both into a plurality of beams of ions having different mass-to-charge ratios, i. e. different specific masses. Each beam is composed of ions of the same specific mass and is collected separately, the current born by the ion beam being an index of the abundance of that kind of ion striking the collector.

The ionization chamber and the analyzer are operated in a highly evacuated state. The electron emitting element must also be operated in a vacuum. It may be disposed in the ionization chamber proper or in an adjacent evacuated chamber. In either case, it is convenient to establish the required vacuum in the several parts of the apparatus by enclosing them in a common envelope of glass or the like which is evacuated by appropriate means, say a diffusion pump operated with oil or mercury followed by a high vacuum pump of conventional type.

The electron emitting element (filament) throws off metal when the pressure in the neighborhood of the element is too high with consequent excessive filament temperature. Under such circumstances, metal may be deposited on the interior surfaces of the apparatus. These deposits affect markedly the operation of the apparatus and should be avoided if possible.

The ion propelling electrodes are maintained during operation at high potential, of the order of 1000 volts, so as to highly accelerate the ions and propel them through the field in the analyzer at relatively high speed. If the pressure in the

neighborhood of these electrodes is too high, undesired ionization of molecules, etc., may occur, and in aggravated instances there may be an actual arcing between the electrodes, with resultant compounding of gas with the metal surface to form undesirable deposits on the interior of the apparatus and with heavy current surges which may overload and damage various elements in the apparatus.

10 In accordance with my invention these and other difficulties are avoided by automatically interrupting the supply of current to the electron emitting element and to the ion propelling electrodes whenever the pressure in the neighborhood of these members rises above a predetermined level. Protective relays are also utilized to prevent injury to the pumping apparatus.

These and other features of my invention will be understood more thoroughly in the light of 20 the following detailed description, taken in conjunction with the accompanying single drawing which is a schematic diagram of automatic controls provided to safeguard the mass spectrometer in accordance with my invention.

25 Referring now to the drawing, it will be observed that a mass spectrometer provided with an analyzer tube 10, an ionization chamber 11 and an electron source in the form of a filament 12 are mounted within an envelope 13 adapted to be 30 evacuated through a pipe line 14. The sample of gas to be analyzed is admitted into the ionization chamber through a conduit 15 connected to a sampling system 16 through a minute orifice 17.

35 Gas molecules entering the ionization chamber are bombarded by electrons of a beam 18 originating at the filament and propelled through the ionization chamber by a potential imposed upon an electrode or shield 20. The molecules bombarded by the electrons are converted into ions. Vagrant electrons pass through the ionization chamber to an electron catcher 21. Ions formed in the ionization chamber are propelled to a slit S₁ at the exit of the chamber by a potential imposed between an electrode 22 which contains this slit and a pusher electrode 23 mounted in the ionization chamber. The ions are further propelled as a heterogeneous beam by a potential imposed between the slit S₁ and a second slit S₂ 45 in an electrode 24 in the head end of the analyzer tube. The two slits match each other and act as a collimator. From the second slit there issues into the analyzer tube a heterogeneous ion beam. This beam is divided into a plurality of diverging 50 homogeneous ion beams under the effects of a

magnetic field imposed in the analyzer tube. Thus the ions are separated according to their specific masses. If the magnetic field or the accelerating voltage or both are varied the separated ion beams may be caused to shift over the exit end of the analyzer tube, which is provided with an exit slit **S₃** and a target **25** upon which ions are collected. The currents which result from the collection of the several ion beams are amplified and recorded in conventional apparatus **26** to produce a mass spectrogram.

The ion accelerating voltages, which are applied between the pusher electrode **23** and the accelerating electrode **22** and between the accelerating electrodes **22-24**, are supplied by a regulated high voltage D. C. power supply **30**, which in turn is supplied with power from a normal lighting circuit or A. C. line **31**. The high voltage power supply feeds a beam sweeper **32** which in turn feeds the pusher electrode and the two accelerating electrodes. A relatively small potential is maintained between the pusher electrode and first accelerating electrode **22** by means of small variable resistance **33**. A relatively large potential is maintained between the two accelerating electrodes **22, 24** by means of a relatively large resistance **34**. Thus the resistances **33, 34** serve as a potential dividing network.

The second accelerating electrode, i. e. that at the head end of the analyzer tube, is maintained at ground potential, as is one end of the large resistance **34**.

The filament is supplied with current by a battery **35**. A D. C. potential difference is maintained between the filament and the surrounding shield **20** by a second battery **36**. A further potential difference is maintained between the shield and ionization chamber wall, which includes the accelerating electrode **22**, by means of a third battery **37**. A fourth potential difference is maintained between the wall of the ionization chamber and the electron catcher **21** by means of the battery **38**.

The envelope and consequently the filament, the ionization chamber and the analyzer tube which the envelope encloses are maintained at low pressure by the vacuum line **14**, into which is connected a diffusion pump **50** of conventional type provided with a heater **51**, and preferably actuated by mercury. Following the diffusion or mercury pump is a second or "fore" vacuum pump **52** which exhausts to atmosphere.

To consider the automatic controls in the apparatus just described, it should be noted that a resistance **60** is provided in the lead to the first accelerating electrode **22**. An increase of current following through this lead (above a predetermined maximum) actuates an automatic control which cuts off the current feed to the regulated high voltage power supply **30**. The two ends of the resistance **60** are connected, respectively, to the anode and cathode of a gas discharge tube **61**. An adjustable battery **62** is connected between the resistor **60** and the anode. A relay **63** is connected in the opposite side of the circuit between the resistor **60** and the cathode of the tube.

The relay is provided with a set of contacts **64** which are normally closed. When the current flowing through the resistor **60** rises above the predetermined level, say 10 microamperes, the tube fires. The increase of current in the resistor **60** brings about a much greater increase in current through the tube, due to ionization therein. It is this phenomenon which causes

the firing and the opening of the relay. When the relay is opened, the high voltage power supply is interrupted on the primary side, thus cutting off the potential applied to the accelerating electrodes in the spectrometer.

The firing of the tube and consequent operation of the relay also opens the circuit connecting the filament **12**, which is the electron source, and its associated battery **35**, this being accomplished by a pair of contacts **65** which are opened by the relay **63**.

The purpose of the automatic cut-offs thus far described is to protect the contents of the envelope against damage from flash-overs and particularly to protect the filament and the accelerating electrodes and the interior of the ionization chamber, from contamination resulting from excessive current.

An ionization type vacuum gauge **70** with the usual associated circuits and apparatus, including a filament **71** is mounted in the conduit **14** between the envelope and diffusion pump and is provided to safeguard the apparatus in the event of the development of high pressure in the envelope. An increase in pressure in the envelope above a relatively low level tends to bring about excessive ionization therein with possible flash-overs and contamination of clean surfaces within the apparatus, thereby destroying the calibration of the system. High pressure in the envelope would also destroy the filament. To prevent such occurrences, an increase in pressure above a predetermined level as indicated by the ionization vacuum gauge **70** is employed to interrupt the supply of current to the high voltage power supply and also to the filament **12** of the spectrometer. Thus the ionization gauge is provided with a relay **73** supplied with current by an associated source not shown. This relay is provided with a pair of contacts **74** which are normally closed and are opened when the ionization gauge indicates an increase in pressure in the envelope above the predetermined level. The relay **73** also opens a second pair of contacts **75** which interrupts the circuit connecting the filament battery **35** and the filament **12** and a third pair of contacts **76** which interrupts the supply of current to the filament of the ionization gauge and prevents it from burning out. In this manner, the ionization gauge cuts off the supply of current to the filament and to the accelerating electrodes of the spectrometer and protects these elements of the apparatus and the interior surfaces of the ionization chamber from damage and contamination due to an increase in pressure, for example an increase caused by a leak in the envelope.

A Pirani gauge **80** is connected to the conduit **14** between the diffusion pump and the fore-pump **52**. This Pirani gauge is of conventional construction and determines a change in pressure in the conduit between the diffusion pump and the fore-pump. If the pressure at this point rises above a predetermined level, a relay **81** connected to the Pirani gauge and supplied with current from a conventional source (not shown) opens a pair of contacts **82**, interrupting the primary side of the regulated high voltage power supply. At the same time, the relay opens a second pair of contacts **83** connected between the filament battery **35** and the filament **12**. In this way, the supply of current to the filament and to the accelerating electrodes of the spectrometer is interrupted as described hereinbefore in connection with the ionization vacuum gauge. At the same

time the Pirani gauge operates to interrupt the supply of current to the heating element 51 of the diffusion pump by means of a relay 85 connected in series with the relay 81 and operating a pair of contacts 86.

The use of the Pirani gauge to automatically interrupt the heating of the diffusion pump saves this latter apparatus from damage in the event of a large leak in the system which supplies so much gas that the diffusion pump would become hopelessly overloaded and fouled.

The supply of current to the heating element 51 may be interrupted by a relay in the same manner as described hereinbefore in connection with the interruption of the supply of current to the primary of the high voltage power supply and to the filament.

In the operation of the apparatus described, the sample is admitted to the ionization chamber at a low but predetermined pressure. Preferably a sample of gas to be analyzed is admitted into a sample bottle 90 of the sample system 16 through a valved inlet 91, after the sample bottle has been evacuated through a valved line 92 by means of a diffusion pump 93 (preferably operated by oil), followed by a fore-pump 94 of conventional mechanical type. To prevent damage to the diffusion pump through overloading, for example when too large a quantity of gas is admitted into the sample bottle or when there is a leak in the system, the apparatus is provided with an automatic protective system similar to that employed between the diffusion pump 50 and the fore-pump 52 for evacuating the envelope of the spectrometer. Thus a Pirani gauge 100 is connected between the diffusion pump 93 and the fore-pump 94. When the pressure between the diffusion pump and the fore-pump arises above a predetermined level the Pirani gauge actuates a relay 101, which opens a pair of contacts 102 and interrupts the supply of current to a heating coil 103 which operates the diffusion pump 93.

I claim:

1. In a mass spectrometer provided with an electron emitting element for producing electrons to bombard molecules and convert them into ions, means for supplying current to the electron emitting element, an analyzer, a plurality of electrodes for propelling ions thus formed through the analyzer, means for flowing current to the electrodes to establish a potential therebetween, and means for evacuating the space within which the electron emitting element and the electrodes are disposed, the improvement which comprises means responsive to an increase in the pressure in said space above a predetermined level for interrupting the supply of current to the electron emitting element and to the electrodes.

2. In a mass spectrometer provided with an electron emitting element for producing electrons to bombard molecules and convert them into ions, an analyzer, a plurality of electrodes for propelling ions thus formed through the analyzer, leads for flowing current to the electrodes to impress a potential therebetween, and for flowing current to the electron emitting element, and means for evacuating the space within which the electron emitting element and the electrodes

are disposed, the combination which comprises a switch connected to said leads, and means responsive to an increase in the pressure in said space above a predetermined level for opening the switch.

3. In a mass spectrometer provided with an envelope, an electron emitting element mounted in the envelope for producing electrons to bombard molecules and convert them into ions, an analyzer, a plurality of electrodes for propelling ions thus formed through the analyzer, means for supplying current to the element to heat it and to the electrodes to impress a potential therebetween, and means for evacuating the envelope, the improvement which comprises means responsive to an increase in pressure in the envelope above a predetermined level for interrupting simultaneously the flow of current to the element and the electrodes.

4. In a mass spectrometer provided with an envelope, an electron emitting element mounted in the envelope for producing electrons to bombard molecules and convert them into ions, an analyzer, a plurality of electrodes for propelling ions thus formed through the analyzer, means for supplying current to the element to heat it and to the electrodes to impress a potential therebetween, and means for evacuating the envelope, the combination which comprises an ionization gauge having a filament disposed in the envelope, means for supplying current to the filament, and means responsive to an increase in pressure in the envelope above a predetermined level as indicated by the ionization gauge for interrupting simultaneously the flow of current to the emitting element, the electrodes and the filament.

5. In a mass spectrometer provided with an envelope, an electron emitting element mounted in the envelope for producing electrons to bombard molecules and convert them into ions, an analyzer, a plurality of electrodes for propelling ions thus formed through the analyzer, means for supplying current to the element to heat it and to the electrodes to impress a potential therebetween, and means for evacuating the envelope, the combination which comprises a conduit having a plurality of vacuum pumps connected in series to the envelope, means connected in the conduit between the envelope and the first pump of the series and responsive to an increase in pressure in the conduit above a predetermined level at the point of connection for interrupting the flow of current to the element and the electrodes and means connected in the conduit following the first pump and responsive to an increase in pressure above a predetermined level in the conduit at its point of connection for interrupting the flow of current to the element and the electrodes and for stopping the pumps.

6. Apparatus according to claim 5 provided with a means for determining a change in the current to the electrodes, and means responsive to said means for interrupting the supply of current to the emitting element and the electrodes when said current rises above a predetermined level.

EDMUND E. HOSKINS.
